DESIGN FOR A PLAYING CARD AND CHIP SET HOLDER OR SIMILAR ARTICLE

Israel Rubinstein, Bronx, N. Y.

Application June 9, 1934, Serial No. 52,119

Term of patent 7 years

To all whom it may concern:

Be it known that I, ISRAEL RUBINSTEIN, a citizen of the United States, residing at Bronx, county of Bronx, State of New York, have invented a new, original, and ornamental Design for a Playing Card and Chip Set Holder or Similar Article, of which the following is a specification, reference being had to the accompanying drawing, forming part thereof.

ing card and chip set holder in the closed condition.

Figure 2 is a perspective view of the same in the open position.

I claim:

The ornamental design for a playing card and chip set holder or similar article, substantially as shown.

ISRAEL RUBINSTEIN.
